VARIABLE TRANSMISSION LEVEL LUFTING
DEVICE FOR DERRICKS AND JIB CRANESRobert Goodman and Henry J. Jacoby,
New York, N. Y.

Application August 11, 1944, Serial No. 549,006

13 Claims. (Cl. 212—8)

1

This invention relates to cranes and derricks having a swinging boom and has for its main object to provide means whereby when the boom is luffed, that is raised or lowered, on its pivot, the hook, with the load thereon, will remain in the same horizontal level.

It is obvious that if no such corrections or adjustments are provided the load will be moved up or down while only a luffing of the boom is needed, and while the operation is for this movement only.

Such a needless raising or lowering of the load during luffing operations will cause complications in the mechanism, will call for heavier structure, will necessitate the use of heavier machinery, and the expenditure of substantial amounts of power and energy without any need or useful purpose for it.

Many methods, schemes, and constructions have been proposed for a so called "level luffing" of derricks or jib cranes, but none of them were practical and none of them provided an exact level luffing. All of them necessitate complicated mechanisms, or entail other drawbacks, while, even so, none of them could provide a real mathematically correct level luffing without any raising or lowering of the load. At best, they could provide, with all their disadvantages, an approximate level luffing only.

The object of this invention is to provide means whereby a substantially mathematically exact level luffing of a derrick or jib crane may be practiced with comparatively simple mechanisms.

Another object of our invention is to provide constructions and means, as characterized hereinbefore, which may be installed into a derrick or crane without otherwise changing their construction or operation, and which, therefore, may be easily installed even into existing old devices of this type.

Still other objects of our invention will be apparent as the specification of the same proceeds.

As has been mentioned, ever since the concept of level luffing for derricks or jib cranes was first introduced, its inherent advantages, both in the saving of power and in details of operation, were at once apparent. But because of the peculiarities of its requirements, most proposed schemes, since developed, at best were only able to develop approximate level luffing, or became so complicated in construction that they could be used only for relatively light loads, since the stresses encountered with the heavy loads made the particular mechanisms required for level luffing extremely bulky or impractical.

2

Many such schemes have been advanced involving compensating hanging pulleys, rotating jibs at the tip of the boom, folding booms, etc. One of the earliest schemes advanced is the twin drum system, one luffing drum and one hook drum so arranged that while the luffing hoist winds in cable to raise the boom, the hook drums will play out cable to keep the load level. This scheme, still basically the simplest scheme ever advanced, did not come into much use precisely because while the theory was sound, the actual results were extremely inaccurate. The inaccuracy of this method lies in the fact that the relative amounts of cable to be wound upon one drum and played out on the other drum to keep the hook level as the boom goes up or down are constantly changing with the changing angle of the boom. Thus, since the diameters of the two drums were fixed, and the gearing between the two drums was constant, the amount of cable run off or on the hook drum for each revolution of the luffing drum was always the same. Thus the original twin drum method attempted to solve, with a constant speed ratio between the two drums, a problem, whose every nature required a variable speed ratio between the two drums, a ratio, in other words, which constantly was undergoing change in the very process of luffing the boom.

The result of this situation was to develop approximate level luffing within a given range when the angular change of the boom was kept within the compass of a few degrees, but as soon as the boom was required to perform over wide changes of radius for the main hook, that is, greatly changing distances from the center of rotation of the crane or derrick, causing the angle of the boom with the horizontal to vary as much as 60° to 70°, it became impossible to even approximate level luffing with this twin drum method.

For this reason, though essentially still the simplest scheme, in theory, this basic method has been discarded for more complicated methods of compensating the hook against the change in vertical height of the boom point to approximate a level hook during the luffing operation.

The effect of our invention to be described herein, is to use standard hoisting and mechanical devices, in combination with our novel elements, so arranged in an unique and new combination that it is possible to achieve, in the basic twin drum method outlined above, substantially perfect and exact level luffing over any range of hook radius and for all or any changes in the angle of the boom with the horizontal.

From the given construction of a crane or derrick, each degree change of boom angle will require a definite amount of compensating cable from the hook drum changing for every degree in the change of the boom angle, and changing with the geometry of the construction of every crane or derrick. Such calculations are readily transformed into requisite ratios between the drums for each absolute angle of the boom with the horizontal.

To achieve this variable ratio between the two drums in a given crane so that exact amounts of compensating cable will be run off or on the hook drum to keep the hook level as the boom is raised or lowered, we have installed between the two drums a variable transmission of any appropriate, but otherwise possibly of standard, manufacture. The ratio between the speeds of the input and output shafts of this transmission will be regulated according to this invention directly by the motion of the boom itself, or of the luffing mechanism.

Our invention of using the motion of the boom itself to regulate the speed ratios of a variable transmission placed between the luffing and hook drums, will cause exact precalculated amounts of compensating cable to be run off or on the hook drum for each revolution of the luffing drum at any and every angle of the boom.

According to this invention the change in ratio between the drums is a continual process constantly taking place under load, thus insuring exact level motion of the load on the hook while the boom is being luffed upwards or down at any angle with the horizontal.

This above described use of a variable transmission operating as a function of the angle of the boom with the horizontal can be readily applied to any existing crane to transform it to a level luffing crane by using a variable transmission of proper horsepower and by installing our novel connection to the boom or to the luffing mechanism to fit the requirements of the geometry of the crane.

This above described method of level luffing is applicable to cranes that handle heavy as well as light loads, since the only extra mechanism needed, the variable transmission, is a mechanical element installed in the crane cab, and does not involve the operation of large structural members, as many other methods do.

In the drawings forming a part of this specification and accompanying the same,

Fig. 1 is a diagrammatic side elevation of a crane, showing our invention installed therein;

Fig. 2 is a diagrammatic plan of the operating mechanism of said crane on a larger scale;

Fig. 3 is a fragmentary detail of a modification, and

Fig. 4 is a detail showing our novel cam secured on the boom of the crane.

Referring now to the drawings more in detail, by characters of reference, the numeral 10 indicates a whirler crane, in general, having a base structure 11, a rotating platform with the upper structure and machinery thereon, indicated by the numeral 12, on which is built the usual boom 13, carrying the load block and hook 14.

As will be seen from the diagrammatic plan of Fig. 2 a main drum 15 is provided for hoisting the load. A load hoisting cable 16 is secured on the drum and is led over a fleeting sheave 16a and other usual constructions, the details of which are not shown, as they are well known to those versed in this art, the cable then is led to a

hoisting block 17. It will be seen that when the drum 15 is operated in the direction of the arrow 18, the load will be hoisted, while if it is operated in the opposite direction, the load will be lowered.

An electric motor 19 provides the power for hoisting the load and also for luffing the boom, when desired, as will be more fully described hereinafter.

10 The motor shaft is connected, through a reducing gearing generally indicated by the numeral 20, to the hoist drum 15, and the structure so far described may be used independently of the rest of our device, when desired, to raise or lower the load, without affecting the position of the boom 13, as will be understood.

15 The motor shaft, however, is extended, as at 21, and is connected through a magnetic clutch 22, with a first or input shaft 23 of a variable transmission device used in our invention, and generally indicated by the numeral 24.

20 This variable transmission may be of any standard type well known in this art, whether hydraulic, mechanical, or electrical, as they are well known in this art, and the one indicated in the drawings will have a second or output shaft 25, a pair of cones 26 on the first shaft 23, and a second pair of cones 27, on said second or output shaft 25, and a wide chain 28 connecting the two double cones in the manner best indicated in Fig. 2.

25 The construction and operation of the variable transmission shown in the drawings is well known in this art. When it is desired to increase the speed ratio between shafts 23 and 25, cones 26 will be caused to near each other, while cones 27 will be moved farther apart, and in this manner belt or chain 28 will be operated by a large driving radius and will operate on a smaller radius 30 so that the speed of shaft 25 will be larger than that of shaft 23. Of course, when it is desired to reduce the speed ratio, the reverse setting of the respective cones 26 and 27 will be executed.

35 The adjustment of the pairs of cones, and ultimately of the speed relation between the input and output shafts may be executed through a control lever 29, pivoted as at 30, the connection to the rest of the mechanism and operation of which will be understood and is well known in this art.

40 Many such double cone and chain type of variable transmission are on the market, and the one which is illustrated in our drawings for an example only, and not in a limiting sense, is manufactured by the Reeves Pulley Co. of N. Y., Inc., and is shown and described in their catalogue, No. G-435 its data given on page 55 and designated by Nos. 000-5. We repeat, however, that many other types of variable speed control devices may be used, whether mechanical, electrical, or hydraulic, controlled by levers, switches, valves, handwheels, etc., their control elements being influenced by the boom similarly as described for lever 29 in the present illustration.

45 The output shaft 25 is connected with a shaft 31, operating the luffing drum, as will be described presently, through a flexible coupling 32.

50 The luffing drum is indicated at 33, and a reducing gear mechanism, generally indicated by the numeral 34, is interposed between the luffing drum 33 and its driving shaft 31.

55 The numeral 35 indicates an emergency hydraulic brake for the main hoist drum drive shaft 21, and the numeral 36 indicates a flexible

coupling between said hoist drum drive shaft and the shaft 37 of the motor 19.

The arrangement of Fig. 2 is for a case where a single motor is used, both for hoisting the load and luffing the boom, while said motor may be used for operating the hoist drum alone, when desired, as will be seen. The luffing cable 38 is secured on the drum 33 and operates the luffing line 39, and it will be seen that upon the operation of drum 33, boom 13 of the crane will be raised or lowered on its pivot 40.

As has been explained hereinbefore, the purpose of our invention is to provide means whereby the load block 14 with the load thereon will always move in a horizontal plane, on any movement, upward or downward, of the boom. For this purpose we provide a novel interconnection between the boom and the variable transmission 24. We secure a specifically designed grooved periphery cam 41 on the boom, to rotate or rock with the same.

In the embodiment shown in our drawings, the pivot pins 42 of the boom are stationary. A small pin 43 may be secured into one of said pivot pins and the cam 41 rotatably arranged thereon. An angular member 44 is secured at one end 45 thereof to the cam, at the other end 46 to the boom. In this manner a rigid permanent connection is established between the boom 13 and the cam 41, and, it will be seen that upon an upward or downward swinging of the boom, the cam will rotate in a right handed or left handed direction on its pin 43.

A control cable 47 is secured at one end 48 to the cam 41, riding in the groove thereof, and at the other end 49 the control cable is secured to the control lever 29, of the variable transmission 24.

It will be obvious that when the boom is moved upwardly, as indicated by arrow 50, cable 47 will be drawn by the cam 41 in the direction indicated by the arrow 51, will move the lever 49 horizontally, as indicated by the arrow 52, and influence the variable transmission 24 in such a manner that the hoist drum 15 will play out a cable exactly sufficient to prevent a raising of the hook 14 with the load thereon, while the boom is moved upwardly, and to keep said hook and load exactly on the same horizontal level, as it has been in the first position of the boom before luffing the same.

In a reverse manner, when the boom is lowered, as indicated by the arrow 53, cable 47 will move in the other direction, arrow 54, the cam 41 playing out a predetermined amount of said cable, and a spring device, diagrammatically indicated at 55, taking up the slackness so produced in cable 47, by swinging the control lever 29 in the opposite direction, (arrow 55a).

In this manner the variable transmission 24 will be influenced in an opposite direction, to a predetermined and precalculated amount, defined by the design of the cam 41, and as the luffing drum 33 lowers the boom, the hoist drum 15 will be idly rotated to take up the cable made loose by the downward swinging of the boom, and, again, keep the load on the same horizontal level, preventing its lowering with the lowering of the boom.

As has been mentioned thereinbefore, from the constructional details and dimensions of a crane, the amount of the cable to be played out by the hoist drum 15, or to be taken up by it, for every angle of luffing of the boom upwardly or downwardly, which may be greatly different at the

various positions of the boom, may be figured out, and the contour of the cam 41 designed accordingly, by methods and calculations well known to engineering experts.

Of course, the data and operation of the variable transmission 24, have to be considered when designing the cam so that the moving of the control lever 29 for said transmission, in one direction or the other, by the cam, should produce such a speed ratio between the input and output shafts 23 and 25 of the variable transmission, that, at a certain position of the boom, a certain amount of luffing thereof should produce such a rotation in one direction or another in the hoist drum 15, as to play out or take up an exact amount of cable needed to keep the load at the previous horizontal level, as will be understood by those versed in this art.

Every crane and every desired path for the load will require a different cam 41, and that shown in the figures is for illustration only. The cam may be designed for a straight horizontal movement of the load, or in case of fast luffing cranes in such a manner that at the start and at the end of the luffing operation the load will be caused to rise to a small extent, to check the luffing operation, or the cam may be designed for any predetermined path for the load, as will be understood and obvious to experts in crane engineering.

It is also to be understood that the principle and use of our invention may be employed for other movements of the boom, different from the one herein described, as when the boom is not raised or lowered but swings on a vertical axis.

When it is desired to raise or lower the load, only, the clutch 22 will be disconnected, so that the motor 19 only acts on the hoist drum 15, and is disconnected from the luffing drum 33.

As has been mentioned, we prefer to employ a magnetic clutch, many of which are well known in this art, but, of course, any other standard type of clutch may be used, operating mechanically, hydraulically, or electrically.

At 56 we show a magnetic brake of any standard manufacture for the main hoist, and at 57 a similar appropriate standard brake for the luffing hoist shaft 31.

It will be seen that in the embodiment illustrated in Fig. 2, one single motor 19 may drive either the hoist drum 15, alone, operating on the load, or both, the hoist drum 15 and the luffing drum 33, for the luffing operation.

In Fig. 3 we show a portion of a modification of this arrangement whereby two motors may be used, one for luffing and one for hoisting the load.

In Fig. 3 the second motor only is shown with the portion of the arrangement wherein it could be attached to the arrangement shown in Fig. 2.

In the modification of Fig. 3, operating with two motors, every part would remain identical to the ones shown in Fig. 2, with the only difference that the magnetic brake 57 is removed from the end 59 of the luffing drum drive shaft 31, and a second weaker motor 60 is attached to said shaft 31, as by a flexible coupling 61.

The magnetic brake 57 will now conveniently be placed at the outer end of the second motor 60.

In this modification there will be no need to use the heavy motor 19 when only a luffing operation is needed. In such a case the second motor 60 would be energized and it would drive the luffing drum 33 and the variable transmission 24, in which the role of the two shafts would be the reverse, shaft 25 being now the input, and 23 the output shaft. Since the motor 19 now receives

no power, its rotor would simply run idly with the rotation of the output shaft 23. The output shaft 23 would then operate the idle hoisting drum 15 through the shaft 21 and gearing 20, as before, the amount of rotation of said drum being defined by the angular movement of the boom 13, through the operation of the cam 41, as before. The heavy motor 19 would be used only for the handling of the load, in which case, magnetic clutch 22 will not be energized, and thereby connected as it is well known in this art.

In case of two motor use, an emergency hydraulic brake for the luffing hoist may be used, and this is diagrammatically indicated at 62.

It also will be seen that the arrangement of the cables 16 and 38, respectively, is such that when the clutch 22 is engaged, and the two drum mechanisms are placed into operation, the drum 15 will wind in its cable 16 when the drum 33 plays out the cable 38, and, vice versa, the drum 15 will play out the cable 16 when drum 33 winds in its cable 38.

With given drum diameters, and given gear reductions for their shafts 21 and 31, the relative amounts of the cables wound on, respectively played off, of the two drums, will be a direct function of the variable transmission 24.

On the other hand, the ratio of speeds of the two shafts in the variable transmission, by our invention, will depend entirely on the boom angle, or the radius of the hook, therefore, the relative amounts of cables simultaneously wound on one drum and off the other, will be a direct function of the radius of the main hook.

When our device is used only to raise or lower the load, without luffing the boom, a main hoist control, indicated diagrammatically at 65, will release the brake 56 and apply the power to the motor 19. Such controllers and their connections to such magnetic brakes and electric motors, are now used and well known in this art, therefore the details of them have not been shown in the drawings.

Clutch 22 also may be of a standard make, and is normally disengaged, as it is well known in this art, and, normally, there is no connection between the main hoist and the luffing hoist, so that upon operation of the controller 65, the crane will only raise or lower the load without influencing the boom.

When luffing operations are desired, a second, luffing, controller 66 will be used, the operation of which will release both brakes 56 and 57, said brakes being, again, any standard constructions, said controller also will engage the clutch 22, as it is well known, whereby power will be delivered for the hoisting or luffing of the boom, and the luffing operation, as described hereinbefore, will take place.

In case the two motor system, or modification of Fig. 3, is used, so as to have the power adapted to the special needs of the luffing hoist only, then in a similar manner as described, the brakes 56 and 57 would be released, the clutch 22 caused to engage, and driving power would be delivered to the motor 60, by well known means, while no power would be allowed to enter the motor 19. Motor 60 would then perform the luffing operation, rotating both drums in the manner described, and the motor shaft of the motor 19 would run idly with a speed transferred to it by the, now output, shaft 23 of the transmission 24, as has been indicated hereinbefore.

At 13' a raised position of the boom is indicated, the changed positions of the hoisting ele-

ments being indicated by 16', 17', and 14' and the changes in the luffing elements being diagrammatically indicated 39', all by dotted lines, and it will be seen that hook H and load L will remain in the same horizontal plane P, as indicated by their dotted positions H' and L'.

Since the position of either shafts in the variable transmission is a function of the position and amount of the cable on the drum, and this, again, is a function of the position of the boom, the principle of our invention, in possibly the simplest manner, may be used in such a way that the position of one of the shafts, itself, will influence the variable transmission in the manner and for the objects described hereinbefore.

From the foregoing description, taken in connection with the drawings accompanying the same, and from the remarks and explanations offered, the advantages and methods of construction and operation of our invention will be readily understood by those versed in the art to which our invention appertains, and while we have described the devices which we now consider to be the best embodiments thereof, we desire to have it understood that they are shown as merely illustrative and not limiting, and that such changes may be made when desired, as are within the spirit of this specification and the scope of the claims hereunto appended.

What we claim as new and want to protect by Letters Patent of the United States is:

1. In a crane, or the like, having an upwardly and downwardly swingable boom on which the load is suspended, a hoisting drum with a hoist cable whereby to raise or lower the load, and a luffing drum to raise or lower the boom, in combination therewith, a changeable driving interconnection between the hoisting drum and the luffing drum, and means controlled by the boom, adapted to continuously influence said interconnection to alter the ratios of rotations between the two drums to desired amounts whereby upon an upward luffing operation said hoisting drum always will play out an amount of hoisting cable calculated to prevent any raising of the load, and vice versa, upon a downward luffing, said hoisting drum always will take up sufficient hoisting cable substantially to prevent a lowering of the load.

2. In a crane, or the like, having an upwardly and downwardly swingable boom on which the load is suspended, a hoisting drum with a hoist cable whereby to raise or lower the load, and a luffing drum to raise or lower the boom, in combination therewith, a variable transmission device between said hoisting drum and luffing drum, and means automatically reacting on the upward or downward movements of the boom and adapted to continuously change the transmission device, said transmission device then changing the relation between the speeds of the luffing and hoisting drums in such a manner that predetermined amounts of hoisting cable will be played out, or taken in, as necessary continuously, and at any position of the boom, to prevent the raising, respectively lowering, of the load during any luffing operation.

3. In a crane, or the like, having an upwardly and downwardly swingable boom on which the load is suspended, a hoisting drum with a hoist cable whereby to raise or lower the load, and a luffing drum to raise or lower the boom, in combination therewith, a variable transmission device between said hoisting drum and luffing drum, and means automatically reacting on the

upward or downward movements of the boom and adapted to continuously change the transmission device, said transmission device then changing the relation between the speeds of the luffing and hoisting drums in such a manner that predetermined amounts of hoisting cable will be played out, or taken in, as necessary, continuously, and at any position of the boom, said means being adapted to cause the load to be raised to a small extent at the beginning and ending of any luffing operation but to keep the load in the same horizontal plane during the rest of the luffing operation.

4. In a crane, or the like, having an upwardly and downwardly swingable boom on which the load is suspended, a hoisting drum with a hoist cable whereby to raise or lower the load, and a luffing drum to raise or lower the boom, in combination therewith, a variable transmission device between said hoisting drum and luffing drum, and means automatically reacting on the upward or downward movements of the boom and adapted to continuously change the transmission device, said transmission device then changing the relation between the speeds of the luffing and hoisting drums in such a manner that predetermined amounts of hoisting cable will be played out, or taken in, as necessary, continuously, and at any position of the boom, said means being adapted to cause the load to describe substantially a predetermined path during the luffing operations.

5. In a crane, or the like, having an upwardly and downwardly swingable boom on which the load is suspended, a hoisting drum with a hoist cable whereby to raise or lower the load, and a luffing drum to raise or lower the boom, in combination therewith, a variable transmission device between said hoisting drum and luffing drum, and means adapted to continuously change the transmission device, the said transmission device then changing relation between the speeds of the luffing and hoisting drums in such a manner that predetermined amounts of hoisting cable will be played out, or taken in, as necessary, continuously, and at any position of the boom, to cause the load to describe respective predetermined paths at respective luffing operations, said means to change said transmission device including a member adapted to influence the transmission device, in one or in the other direction, upon its movement in one or the other direction, and means interposed between said member and the boom of the crane adapted to move said member with the movements of the boom in a predetermined manner.

6. In a crane, or the like, having an upwardly and downwardly swingable boom on which the load is suspended, a hoisting drum with a hoist cable whereby to raise or lower the load, and a luffing drum to raise or lower the boom, in combination therewith, a variable transmission device between said hoisting drum and luffing drum, and means adapted to continuously change the transmission device, said transmission device then changing the relation between the speeds of the luffing and hoisting drums in such a manner that predetermined amounts of hoisting cable will be played out, or taken in, as necessary, continuously, and at any position of the boom, to cause the load to describe a predetermined path during respective luff operations, and said means to change said transmission device including a pivoted lever influencing the transmission device, a spring having the tendency to keep said lever in a normal position, an element influenced by the an-

10
5

gular movements of the boom, and a connection between said element and said lever, whereby the movement of said element upon the luffing of the boom in one direction will rock said lever out of its normal position, while an opposite movement of said element will cause a rocking of said lever towards its normal position.

7. In a crane, or the like, having an upwardly and downwardly swingable boom on which the load is suspended, a hoisting drum with a hoist cable whereby to raise or lower the load, and a luffing drum to raise or lower the boom, in combination therewith, a variable transmission device between said hoisting drum and luffing drum, and means adapted to continuously change the transmission device, said transmission device then changing the relation between the speeds of the luffing and hoisting drums in such a manner that predetermined amounts of hoisting cable will be played out, or taken in as necessary, continuously, and at any position of the boom, to cause the load to describe a predetermined path during a luffing operation, said means to change said transmission including a member on said transmission adapted to move in one or other directions, and thereby influence said transmission to effect higher or lower speed ratios, respectively between the hoisting and luffing drums, a cam rotatable on the pivot of the boom, a connection between the boom and the cam, whereby the cam will rotate in proportion to the angular movements of the boom, and a connection between said cam and said member on the transmission device whereby said member will react on the movements of the cam in a predetermined manner.

8. In a crane, or the like, having an upwardly and downwardly swingable boom on which the load is suspended, a hoisting drum with a hoist cable whereby to raise or lower the load, and a luffing drum to raise or lower the boom, in combination therewith, a variable transmission device between said hoisting drum and luffing drum, and means automatically reacting on the upward or downward movements of the boom and adapted to continuously change the transmission device, said device then changing the relation between the speeds of the luffing and hoisting drums in such a manner that predetermined amounts of hoisting cable will be played out, or taken in, as necessary, continuously, and at any position of the boom, to cause the load to describe respective predetermined paths at respective luffing operations, an electric motor to drive the hoisting drum shaft, means to disconnect said shaft from the hoisting drum and means then to connect it to the respective end of said transmission device, for a luffing operation, said last two disconnecting and connecting means being adapted to act in the reverse manner for a hoisting operation.

9. In a crane, or the like, having an upwardly and downwardly swingable boom on which the load is suspended, a hoisting drum with a hoist cable whereby to raise or lower the load, and a luffing drum to raise or lower the boom, in combination therewith, a variable transmission device between said hoisting drum and luffing drum, and means automatically reacting on the upward or downward movements of the boom and adapted to change the transmission device, said transmission device then changing the relation between the speeds of the luffing and hoisting drums in such a manner that predetermined amounts of hoisting cable will be played out, or taken in, as necessary, continuously, and

at any position of the boom, to cause the load to describe a predetermined path during a luffing operation, a first electric motor normally connected to said hoisting drum, and adapted to drive the same, means to disconnect said hoisting drum from said transmission device when hoisting, a second electric motor normally connected to and adapted to drive said luffing drum, and means to connect said transmission to said hoisting drum, means to de-energize said first motor, and means to energize said second motor, when luffing.

10. In a crane or the like, having a boom, a hoisting and a luffing drum, a combination, of a shaft operatively connected to the hoisting drum, a shaft similarly connected to the luffing drum, a variable transmission device between said two shafts to determine the ratio between their speeds, means adapted to change said variable transmission device and thereby change the ratio of rotation between said two shafts, and means to continuously influence said transmission changing means in accordance with the movement of the boom.

11. In a crane or the like, as set forth in claim 10, said means to continuously influence the transmission changing means including a cam secured on and rockable with the boom.

12. In a crane or the like, as set forth in claim 10, said means to continuously influence the transmission changing means including a cam rockable with the boom, a lever connected to said ratio changing means, and a connection between said cam and said lever.

13. In a crane, or the like, having an upwardly and downwardly swingable boom on which the load is suspended, a hoisting drum with a hoist cable whereby to raise or lower the load, and a luffing drum to raise or lower the boom, in combination therewith, a variable transmission device between said hoisting drum and luffing drum, and means automatically reacting on the up-

ward or downward movements of the boom and adapted to continuously change the transmission device, said device then changing the relation between the speeds of the luffing and hoisting drums in such a manner that predetermined amounts of hoisting cable will be played out, or taken in, as necessary, continuously, and at any position of the boom, to cause the load to describe respective predetermined paths at respective luffing operations, a source of power to drive the hoisting drum shaft, means to disconnect said shaft from the hoisting drum, and means then to connect it to the respective end of said transmission device, for a luffing operation, said last two disconnecting and connecting means being adapted to act in the reverse manner for a hoisting operation.

ROBERT GOODMAN.
